ELECTROLYSIS OF AQUEOUS SALT SOLUTIONS IN LIQUID CATHODE CELLS

Benjamin Woolf Hirsh, Welwyn Garden City, England, assignor to Imperial Chemical Industries Limited, a corporation of Great Britain

Application September 9, 1946, Serial No. 695,804
In Great Britain August 27, 1941Section 1, Public Law 690, August 8, 1946
Patent expires August 27, 1961

2 Claims. (CL 204—99)

1

This invention relates to an improved process for electrolysis, and more particularly to an improved process for the electrolysis of aqueous solutions of alkali metal chlorides using a mercury cathode.

The manufacture of chlorine and solutions of caustic soda of high purity by electrolyzing aqueous solutions of sodium chloride using a mercury cathode, and subsequently, decomposing the sodium amalgam which is formed, is a well known industrial process. Many forms of apparatus have been proposed for carrying out such processes and, in fact, it appears that substantially all advances which have been made in this art for a considerable time past have involved refinements in the construction of the cell structures used in these processes. Notwithstanding these various refinements, the electrolysis of aqueous saline solutions using liquid electrode cells has heretofore involved certain undesirable features, e. g., relatively large voltage and current requirements and, also, low efficiency of operation.

A principal object of this invention is the provision of a new and improved process for the electrolysis of aqueous saline solutions in flowing, liquid electrode cells. Another object is the provision of electrolytic processes which require a relatively low operating voltage. A still further object is the provision of such processes which are capable of close control upon the reactions taking place in the electrolytic cell. Still further objects and the entire scope of applicability of this invention will become apparent from the detailed description given hereinafter.

These objects are accomplished according to the process of the present invention by operating the electrolysis of aqueous solutions in liquid electrode cells, so that the electrolyte is caused to flow through the inter-electrode space between a solid anode and the flowing liquid cathode at a high velocity relative to the anode.

The success of the present invention depends to a large extent upon the discovery that a very marked reduction in the operating voltage in cells of the subject type is obtained by increasing the velocity of the electrolyte flow in the inter-electrode gap above a required high velocity. While the absolute reason for the unusual results obtained by the use of this discovery are not certain, it appears that, among other things, the high velocity electrolyte flow aids in the removal of gas bubbles from the surface of the solid anode causing a diminution of the operating voltage requirements of the cell. Thus, in operating cells of the subject type with electrolyte speeds which

2

have been considered necessary heretofore, i. e., normally below 2 cm. per second and usually between 0.25 and 1 cm. per second, stationary bulbs of chlorine gas collect on the under-surface of the anode and increase the electrical resistance of the apparatus requiring higher operating voltage than should theoretically be needed. It has been found that these bulbs of gas persist even with electrolyte velocities substantially in excess of the customary values, as indicated above, but it has now further been found that, as the inter-electrode velocity of the solution is increased above a value of the order of 7.5 cm. per second, that a unique diminution of the operating voltage of the cell results apparently due to the lack of stationary gas bulbs upon the anode surface. Precise measurements of the velocity of the electrolyte are not easy to make in practice, but for any given cell the conditions of the invention may be determined by varying the electrolyte flow in the inter-electrode gap and noting the corresponding cell voltage. Factors other than gas bubble prevention also are probably involved in the operation of the unique features of this invention but, whatever may be the explanation, it is a fact that, as a certain brine velocity is reached, it is found that a diminution in the cell voltage occurs, and it can be taken that, when this has occurred, a suitable electrolyte velocity has been reached. In accordance with the present invention it is possible to operate the electrolysis consistently at a voltage of from 3.5 to 3.7 and cathode current density in excess of 120 amperes per square foot, e. g., 150 amperes per square foot as compared with the standard operation of from 4 to 5 volts under such condition of current density.

Further increase in the velocity of the solution produces some further diminution in cell voltage due to the diminution reached in the ratio of the volume of gas to the volume of solution in the electrolyte. With still further increases in the velocity, the further gain in energy consumption due to this cause would tend to be counterbalanced by the increased cost of circulating electrolyte.

The general mode of operation of electrolysis of saline solutions to produce caustic soda and chlorine of high purity according to the procedure of this invention may be briefly stated as follows: The apparatus used in the process preferably consists of a trough-shaped vessel with a smooth plane bottom. A vessel is used which is long in comparison with its width and is arranged at a slight angle to the horizontal, so that the liquid

cathode can be caused to flow along the plane surface of the bottom as a continuous sheet. The anode electrode of the cell consists of a number of formed, closely spaced graphite plates or blocks which are held by means of carbon rods passing through the cover of the cell, so that the under-surfaces of these graphite plates are substantially parallel to and a short distance above the surface of the liquid cathode. In order to obtain the high velocity of the electrolyte flow which is essential to the process, the electrolyte is either introduced into the cells under super-atmospheric pressure or the outlet of the cell is maintained under sub-atmospheric pressure. In order to accomplish this, the cell is provided with a suitable cover and means for sealing the cell from the atmosphere. Such cells are, for example, described in copending application, Serial No. 695,622, for Electrolysis, filed by John Glass and Charles Carter, on September 9, 1946; Serial No. 695,623 for Electrolytic Cells, filed by Charles Carter and Arthur W. Ravenscroft, on September 9, 1946, and in U. S. Patent No. 2,503,337. The liquid cathode employed in the operation of the cell is preferably mercury, but it should be realized that, as the electrolysis proceeds, the pure metal becomes amalgamated with the sodium produced in the process, so that the amalgam formed continuously increases in strength. Therefore, the word "mercury" as used in this specification and the appended claims, should be understood to cover the resulting amalgam as well as the metal, unless the context requires the narrower meaning. In use, the mercury is caused to flow through the cell at a controlled rate with the saline electrolyte solution flowing through the cell as indicated herein in the gap formed between the flowing mercury cathode and the stationary solid graphite anodes. The chlorine evolved in the inter-electrode space during the process is removed at a suitably spaced interval from the inter-electrode space by means of suitably arranged exhaust pipes.

In order to give a better understanding of the nature of the apparatus which can be used to carry out the new methods of this invention, one usable form thereof is illustrated in the attached drawing, in which:

The figure is a vertical sectional view of a form of cell having skirts deviating from the cell cover and sealed to a flat base by means of a resilient sealing ring or member.

Referring in detail to the drawing, the flat base portion 1 carries the flowing mercury cathode 2 and the aqueous electrolyte 3 above the mercury cathode.

The cell has a cover 4 of steel, lined with insulating material 5, resistant to the products of electrolysis. Cover 4 carries a number of solid carbon anode blocks 6 (one of which is shown) each depending from carbon rods 7 which pass through openings in the cover 4 and through which current is supplied to the anode from a current source (not shown). In this form of cell, the anode rods 7 are sealed by a sealing composition 8, but other suitable methods for making a gas-tight joint may be employed.

The cover 4 is provided with a depending skirt 9 also lined with insulating material 5. These skirts extend down below the level of the mercury cathode 2 and a liquid-tight joint is formed between the depending skirts and the base portion 1 by an endless band of sponge rubber 10 having an impermeable outer skin carried in the semi-cir-

cular peripheral groove 11 formed in the base portion 1.

On the sides of the cover 4 are horizontal lugs 12 which serve to support the cover 4 at any desired height upon the pillar-bolt 13 threaded into the stand 14. The collars 15 and locknuts 16 permit the height of the cover 4 relative to the base 1 to be properly adjusted.

The space running the full length of the cell between the anode cover 4 and the anode 6 is freely accessible to the electrolysis gases which are led out of the cell by one or more gas outlet tubes 17 which are sealed to the cell cover by sealing composition 8. Although there is free space above the anode, the actual flow of electrolyte is substantially restricted to the inter-electrode gap by the process gas pressure above the anode and by placing the electrolyte exit horizontally in line with the gap.

The drawing is diagrammatic and employed only to allow for better comprehension of the written description of the invention. Different forms of apparatus can be used in carrying out the new process, as has been indicated above, and further discussion and illustrations of usable apparatus can be found in the patent applications and patents listed above.

The operation of my invention may be more fully comprehended by reference to the following illustrative examples in which all parts are by weight, unless otherwise specified.

Example I

Electrolysis of an aqueous solution of sodium chloride is accomplished in an electrolytic cell long in comparison with its width having a plane bottom surface consisting of a flat steel plate, inclined at a slope of 1 in 300 to the horizontal, adapted to carry a flowing mercury cathode. The cell has also a cover provided with a depending, rigid skirt adapted to fit loosely over the flat steel plate. A resilient packing, such as sponge or inflated rubber is positioned in a peripheral groove on the steel plate so as to make a liquid-tight seal between the skirt and the steel plate. Adjusting means are also provided whereby the cover can be maintained at any desired height with reference to the steel plate which carries the mercury. Graphite anode blocks are arranged to fit closely to the cover and the inside wall of the skirt and are provided with suitable slots or perforations surmounted by off-take pipes, each extending to a height above the cell greater than the pressure of brine generated below the off-take, and thus forming vents to permit the escape of the chlorine formed during the electrolysis. The area of the mercury-carrying cathode surface is approximately 80 square feet and the distance between the graphite anodes and the steel surface carrying the mercury is about 6 mm.

An aqueous solution of sodium chloride of 25% concentration is supplied to the cell under a hydrostatic head corresponding to 0.036 lb. per square inch per foot length of the cell. The velocity of the brine along the cell relative to the anode surface, calculated on the assumption that the brine flow is restricted to the interelectrode space, is 42 cm. per second. The true velocity is somewhat less than this figure owing to inaccuracies in the fitting of the anodes to the cover which lead to some bypassing of the brine flow. The cell operates at a voltage of 3.51 volts and a current of 12,000 amperes when the brine temperature is 70° C.

Example II

Using the apparatus of Example I an aqueous sodium chloride solution of 25% concentration is electrolysed with an identical graphite to steel gap with the electrolyte introduced into the cell under a hydrostatic head corresponding to 0.024 lbs. per square inch per foot length of cell. The linear velocity, calculated as above, is 21 cm. per second. Using a cathode current density of 149 amperes per sq. ft. the gas volume to solution volume in the fluid leaving the interelectrode space is approximately 1 to 5.8 and the cell voltage is 3.63 volts.

The velocity which gives satisfactory values for the gas/solution ratio will vary with such factors as the current supplied to the cell, the inter-electrode gap and the distance between successive points at which chlorine can escape from under the anode; in practice, however, it is found that the velocity chosen with respect to gas/solution ratio is always greater than that which suffices to remove the stationary bubbles of chlorine from the lower face of the anode.

The velocity in the inter-electrode space may be attained by increasing the slope of the cell bottom sufficiently; however, the necessary high slope will entail loss of current efficiency which may off-set the gain due to reduced cell voltage. Preferably, therefore, a cell is employed which is capable of operating under conditions involving the maintenance of a pressure within it different from atmospheric, and the increased velocity in the inter-electrode space is secured by increasing the hydrostatic head under which the solution to be electrolyzed is delivered to the cell. In using a mercury cell of the type hitherto employed in which there is a gas space above the anodes, difficulties arise due to the tendency of the electrolyte to flow above the anodes and unduly high pressures would be required to achieve the desired velocity in the inter-electrode gap. Advantageously, therefore, the process of the invention is carried out in such a manner that the electrolyte is caused to flow through the cell solely through the inter-electrode gap, and the evolved chlorine gas is drawn off at intervals from the inter-electrode gap. A suitable form of cell for the process is one in which the anode fills substantially the whole of the cell above the inter-electrode gap, vents for the chlorine being provided each extending to a height greater than the head of electrolyte developed beneath it before joining a common header. In such a cell, there is a close correlation between the pressure difference between the ends of the cell and the velocity of the solution being electrolyzed in the gap. This pressure difference depends to a large extent on the conditions and on the size of the cell. It is, therefore, not practicable to specify the pressure difference to be used until the conditions are known. However, when it is apparent that suitable velocity conditions in a particular installation are established, then it is found more convenient to use the pressure drop, which can be directly observed, to verify that suitable operating conditions are maintained in the cell, rather than to rely on a determination of the velocity in the narrow inter-electrode gap. The latter must nec-

essarily be made indirectly from measurements of the volume of solution delivered to the cell in a given time, and from the geometrical configuration of the cell.

5 In using the apparatus for carrying out the process of the present invention, an alkali metal chloride solution is supplied to the cell under a comparatively large hydrostatic head so that the velocity of the solution between the electrodes is 10 above the required high velocity as hereinbefore defined. Alternatively, the electrolyte may be supplied at atmospheric pressure and the increased velocity achieved by applying suction to the exit by which the spent solution leaves the 15 cell.

As many and varied modifications of the subject matter of this invention will become apparent to those skilled in the art from the detailed description given herein, it should be understood 20 that this invention is to be limited only in accordance with the appended claims.

I claim:

1. The process for the electrolysis of aqueous solutions of alkali metal chlorides between a 25 closely spaced solid graphite anode and a flowing mercury cathode which comprises restricting the flow of the electrolyte substantially to the inter-electrode space and causing the electrolyte flow to exceed a velocity, relative to the anode, of 30 7.5 cm. per second by maintaining a fluid pressure differential between the inlet and outlet of the inter-electrode gap sufficient to cause said flow.
2. The process according to claim 1 in which 35 said electrolyte flow above said critical velocity is obtained by restricting the flow of electrolyte substantially to the inter-electrode space and creating a substantially higher pressure upon the inlet end than upon the outlet end of said space.
